UNITED STATES PATENT OFFICE.

ARTHUR M. WILSON, OF WHITE PIGEON, MICHIGAN, ASSIGNOR OF ONE-HALF HIS RIGHT TO WILLIAM R. GILLETT, OF SAME PLACE.

IMPROVEMENT IN WASHING-MACHINES.

Specification forming part of Letters Patent No. 142,313, dated August 26, 1873; application filed May 31, 1873.

To all whom it may concern:

Be it known that I, ARTHUR M. WILSON, of White Pigeon, in the county of St. Joseph and State of Michigan, have invented a new and valuable Improvement in Washing-Machine; and I do hereby declare that the following is a full, clear, and exact description of the construction and operation of the same, reference being had to the annexed drawings, making a part of this specification, and to the letters and figures of reference marked thereon.

Figure 1 of the drawings is a representation of my machine in side elevation. Fig. 2 is a transverse vertical section of the same; and Fig. 3 is a section through one of the end pieces of the frame.

This invention has relation to a washing-machine; and the novelty consists in the construction of a frame having a number of slots and rollers, as hereinafter described and claimed.

In order to enable others skilled in the art to which my invention appertains to make and use the same, I will now proceed to describe its construction and operation.

Like letters of reference indicate corresponding parts in the several figures.

A A represent the side pieces, which, with suitable connecting-bars, form the frame of my machine. In the center of each side piece A, from the top downward, is a vertical slot, a , of suitable width to receive boxes b b , and from the bottom of said slot a extends downward a narrower vertical slot, a^1 , to receive

the journals d d of the large corrugated or fluted washing-roller B. On each side above this roller B is a smaller roller, C, similarly corrugated or fluted, and the journals e e of these latter rollers rest in inclined slots a^2 a^2 . On top of each journal e is placed a spiral spring, f , which is held down by means of a pin, h , as shown in Fig. 3. By means of the pins h the tension of the springs f f may be increased or reduced at will, so as to regulate the pressure of the upper smaller rollers C C on the lower larger roller B, according as thick or thin garments are to be passed through and washed. In the bottom of each slot a is placed a spiral spring, f' , upon which the lower box b rests. The journals of the two wringer-rollers D D have their bearings in the boxes b b , and the pressure of said rollers is regulated by means of set-screws k k , operating on top of the upper boxes.

What I claim as new, and desire to secure by Letters Patent, is—

The combination of the side pieces A A, having slots a a^1 a^2 , small rollers e e arranged above the large roller B, springs f f , and regulating-pins h h , operating in the manner as specified and shown.

In testimony that I claim the above I have hereunto subscribed my name in the presence of two witnesses.

ARTHUR M. WILSON
